MULTIPLE ZONE CONTROL APPARATUS
Richard O. Chamberlain, Caliente Ranch, and Charles E. Wakefield, Jr., Bakersfield, Calif., assignors to Richfield Oil Corporation, Los Angeles, Calif., a corporation of Delaware

Filed June 29, 1955, Ser. No. 594,845
6 Claims. (Cl. 166—185)

This invention relates to an apparatus for use in systems adapted for selectively controlling the flow of oil, gas or other fluid from or into a plurality of vertically spaced formations adjacent a well bore. More particularly, this invention is concerned with means for facilitating removal from a well of an apparatus designed to block flow from an adjacent formation.

In our copending application Serial No. 473,782, filed December 8, 1954, now Patent No. 2,869,645, we have disclosed a system for controlling flow of fluids injected into and removed from a plurality of vertically spaced producing formations adjacent a cased well bore. We also have disclosed in that application and in our copending application Serial No. 489,245, filed February 18, 1955, now abandoned, certain control structures for use in the described system. As discussed in our prior applications, for maximum efficiency in controlling wells having a plurality of vertically spaced producing formations it is essential that control means employed be removable or insertable without the necessity of removing or otherwise disturbing other control members at different levels.

In a system where control of fluid flow is being exercised at a plurality of vertically spaced points in a well, it is often desired to stop flow into or from the well tubing at a given level. This can be done in the systems of our said copending applications by using flow control members or valves at the given level which shutoff communication between the tubing and the adjacent formation. The usual control means of our system comprises an elongated valve control member which is placed in a valve seat at a desired level in the well. The valve seat is offset from the vertical axis of the tubing so that the valve control member can pass through the tubing past the valve seat. The valve member is centrally bored and fluid passes through the bore in going from the tubing to the formation or vice versa.

When it is desired to cutoff communication with a given formation, a special flow control member is placed in the tubing in a valve seat opposite that formation. The central bore of this flow control member is occupied so that fluid cannot traverse the bore. This could be accomplished by providing a solid flow control member, i.e. one having no through bore; however, in order that the control members be usable under a variety of flow conditions, they are preferably constructed so that a solid but removable member (for convenience referred to as a solid bean) can be placed across the bore. Thus the bore of the usual flow control member becomes blanked-off in simple fashion. As explained in our copending applications, the solid bean can be replaced by a member or bean having an orifice therethrough of a given size to provide a desired flow rate through the control member.

This system of well operation has in general proved satisfactory; however, difficulty has been experienced in removing flow control members from their valve seats when the bore of the control member is occupied by a solid bean. For instance, in those cases where the pressure within the flow string is greater than the reservoir pressure opposite the level of the solid bean, a rather large force can develop as a result of the differential pressure to cause the control member to be held firmly in position in the valve seat even if the anchoring means

2

for the control member be released. Inasmuch as fishing tools used for placing or removing these control members are run in on a small, piano-type wire line, this differential force frequently cannot be overcome before breaking the line. The instant application is directed to a flow control member modified to eliminate such differential pressures and facilitate removal of the member from the well tubing. This removal might be effected in order that the solid bean can be replaced by an orificed member establishing regulated flow to a given vertical position of the well bore.

Our invention will be most readily understood by reference to the attached drawings in which:

FIGURE 1 is a vertical section of the lower portion of a valve control member of the present invention having an orifice plugging rod inserted in the bore of valve control member and an aperture disposed in its bottom conical section.

FIGURE 2 is a vertical partial section of an embodiment of an upper portion of a valve control member of the present invention showing a suitable latching means and the relationship of the orifice plugging rod to the latching member.

FIGURE 3 is a vertical section of the lower portion of a second embodiment of a valve control member of the present invention having a short orifice plugging rod inserted in the bore of the valve control member.

FIGURE 4 is a fragmentary elevational view with parts broken away, of the valve control member of FIGURE 1 disposed within a valve seat of a tubing section within a well casing.

FIGURE 5 also is a fragmentary elevational view with parts broken away, of the valve control member of FIGURE 3 disposed within the valve seat of a tubing section within a well casing.

FIGURE 6 is a partial vertical section of the latching member showing cut-away slots to permit its rotation, and

FIGURE 7 is a top view taken along section B—B of FIGURE 2.

FIGURE 8 shows a tool used to remove the valve control member from the valve seat.

Referring now to the drawings, FIGURES 3 and 5 constitute one embodiment of the invention and FIGURES 1 and 4 a second embodiment. Both embodiments hold in common the following members designated by like numerals: the numeral 9 designates a perforated well casing and 10 represents a tubing section which is provided with a through bore 8 and with laterally enlarged portion 12 intermediate its ends. Section 10 is advantageously adapted at its ends to be engaged in a tubing or pipe string in a well bore. In the laterally enlarged portion 12 is a generally circular valve seat 14. As shown, valve seat 14 is defined by the outer wall of the laterally enlarged portion 12 of the piping section 10 and wall 16. The wall 16 separates the valve seat 14, along a portion of its length, from horizontal communication with the through bore 8 of piping section 10. Strap 18 is provided to facilitate retention of the valve control member within the valve seat. Advantageously retaining means 18 can be formed by removing a section of wall 16 to provide a ring-like retaining member.

Disposed within the valve seat of the laterally enlarged portion 12 of piping section 10 is the centrally bored valve control member means 20. Advantageously, valve means 20 may be composed of a plurality of threadingly engaged sections comprising an upper portion 22, an intermediate portion 24 and a bottom portion 26. The valve means can be a single unitary structure adapted to have the characteristics disclosed below or it may be composed of a plurality of sections as illustrated. When the control member 20 is composed of a plurality of separable sections it should

be understood that suitable O rings such as at 48 in FIGURES 1 and 3, can be included where an absolute seal is desired. Inserted within bored valve member 20 of both FIGURES 1 and 3 is bean plugging rod 60, threadedly engaged to cylindrical member 61 (FIGURE 2) in the upper portion 22 of valve means 20. The upper portions 22 of the separate embodiments are similar and the common structure is shown in FIGURES 2 and 6 to 8.

The two embodiments differ as follows. A removable restricted orifice member or bean member can be placed within the bottom portion 26 as designated by numeral 36 in FIGURE 1, or at a point in member 24 below the aperture 21 as designated by 25 in FIGURE 3. In the embodiment of FIGURE 1 the rod 60 extends longitudinally downward to enter the orifice of bean member 36. In the embodiment of FIGURE 3 a solid bean 38 occupies the position of member 36 in FIGURE 1 and a relatively short rod 60 is utilized, extending downwardly to enter the orifice of bean member 25. Solid bean 38 is not a necessity in the embodiment of FIGURE 3. The lower ends of the rods 60 are sized to prevent any substantial fluid flow through the members 25 and 36. If desired, but less advantageously, the orifice can be formed by the walls of member 20 or the orifice could simply be the bore of member 20. To prevent fluid leakage or by-pass, the beans 36 or 25 can be supplied with O rings 36b or 25b respectively. The removable orifice members 36 and 25 have their longitudinal axis in substantial alignment with the axis of the bore of the valve means 20 above and below it. The diameter of the throat of the restricted orifice may vary and when effective in restricting flow is less than the diameter of the bore of the valve control member 20.

In the embodiment of FIGURES 1 and 4 fluid flow between a formation opposite the section 10 and the bore of the valve means is effected through an aperture 44a as in the inwardly tapering valve seat bottom 44 of the laterally enlarged piping section 12. With this arrangement, an aperture 42 is provided in the end conical section of the bottom portion 26 of the valve means 20 to communicate the bore of the valve means 20 and aperture 44a. Therefore the fluid flow path in FIGURES 1 and 4 includes apertures 44a and 42, the orifice of member 36 and apertures 21 and 37 with lower seal 54 providing a flow barrier around the valve body.

In the embodiment of FIGURES 3 and 5, instead of apertures 44a and 42, an aperture 29 is provided in the intermediate portion 24 above the blank bean 38. Apertures 29a are provided in valve seat 14 opposite aperture 29. The fluid flow path in FIGURES 3 and 5 is through apertures 29a and 29, the orifice of member 25 and apertures 21 and 37 with an upper seal 54 provided between the valve seat and the valve control member between apertures 29 and 21.

It should be observed that the restricted orifice member receiving rod 60 to be effective in stopping flow to and from the formation must be placed between the aperture communicating the bore of the valve control means 20 with the bore of the piping section 8 and the aperture communicating the bore of the valve means with the exterior of section 10 and thus with the well formation via casing 9.

To sealingly seat the valve means 20 of either of the embodiments in the drawings within their respective valve seats, resilient packing seals 54 are provided. By placing the seal 54 between the aperture communicating the bore of the valve means with the bore of the piping section and the aperture communicating the bore of the valve means with the formation through the valve seat, flow of fluid to and from the formation can be prevented from passing through the length of the valve seat unless it passes by means of the bore in the valve means. These seals may be of any construction and be disposed on either the valve seat or valve body but resilient seals on the valve body are preferred.

The upper portion 22 of the valve means 20 includes head 28 (refer to FIGURE 2) associated therewith and

adapted to permit engagement with a well stringing tool (not shown in FIGURE 8) which is capable of inserting the valve means into and removing the valve means from the valve seat (see U.S. Patent No. 2,679,903). Circumferentially disposed about the upper portion 22 is a shouldered projection 30. Shoulder 30 engages retaining means 18 (FIGURE 4) so that the valve means 20 is prevented from moving downwardly into the valve seat to an extent further than desired. Spaced below the shoulder 30 is a latching means 32 which is rotatably mounted on a pin 67 horizontally positioned through opposing walls of the upper portion 22 of valve control member. The latch cam 32 includes a latching finger 33 which projects outwardly through vertical slot 56 when in horizontal position. Except for the necessary modifications, the latching member may take the form and operate as described in U.S. Patent No. 2,679,903 to permit latching engagement with the lower side of the retaining means 18.

The modifications involve a center opening 66 (refer to FIGURES 6 and 7) directly through latch cam 32 and pin 67 to permit the free passage of bean plugging rod 60, and cut-away slots 71, 72, 73 and 74 joining center opening 66 to allow for rotation of the latching means. As shown in FIGURE 6, the slots 71, 72, 73 and 74 are cut away from cam latch 32 at angles of approximately 40° or 45° from the center opening to the periphery of the latch cam 32. The slots are cut away from each side of center opening 66 through which bean plugging rod 60 passes at approximately the middle section of latch cam 32 (see FIGURE 7). Consequently, even though the bean plugging rod passes through the latch cam, it is able to rotate when it is desired to remove the valve means 20.

Prior to installing the flow valve of this invention, the bean plugging rod is set so as to insert into the orifice of member 36 or 25, that is, members 28, 63 and 61 are depressed until member 61 holds cam 32 so that projection 33 is in the horizontal position of FIGURE 2. Then pin 61 is inserted to hold these parts in this relationship. With the bean plugging rod in this position member 20 can be latched into a desired valve seat of the tubing string since spring 65 at one end is attached to cam 32 and at the other end engages the side of member 22 in a manner to permit upward movement of projection 33 while it passes by strap 18. Spring 65 tends to force the cam 32 in a clockwise direction and will move projection 33 until it points downwardly sufficient to be retracted into slot 56 of member 22. Downward movement of member 33 is stopped by rod 61. As a consequence of the latching of member 20 in the valve seat flow from the adjacent formation is blocked. Installation of member 20 can be accomplished as described in U.S. Patent No. 2,679,903.

To remove the valve control member 20, fishing tool 70 is lowered to engage the under portion of the conical projection 28 of the upper portion 22 of the valve means. By raising the tool, the pin 62 which connects slidable rod 63 to the body member 64 is sheared and by reason of the resulting upward movement of the rod 63, the latch cam 32 is released from the cylindrical catch member 61 and rotates on horizontally positioned pin 67 so that the finger 33 is retracted through the vertical slot 56 by the action of the spring 65. At the same time, the bean plugging rod, being threadedly connected to the cylindrical catch member 61 or rod 63, moves upwardly so that the bottom end of the bean plugging rod is withdrawn from the hole in the bean thereby opening the bean. The opening of the bean equalizes the pressure within the flow string with the pressure in the formation opposite said tools. Equalizing the pressure in the inside and outside of the valve means thus allows the valve control member to be easily withdrawn from the tubular valve seat.

We claim:

1. An apparatus comprising an elongated, generally

cylindrical member having a longitudinal bore, a first aperture through the wall of said cylindrical member communicating with said bore, a second aperture through the wall of said cylindrical member communicating with said bore and vertically spaced below said first aperture, a removable member in said bore between said first and second apertures and having a through longitudinal orifice, retractable means in said bore extendable to plug said orifice for preventing fluid flow through the bore between said first and second apertures, means for releasably holding said retractable means in flow-preventing position, a member pivotally mounted in said cylindrical member, means biasing said pivotally mounted member towards a position in which it does not extend radially beyond said cylindrical member, means associated with said retractable means for positioning said pivotally mounted means so that it projects outwardly from said cylindrical member when said retractable means is held in flow-preventing position, and means for releasing said holding means and said means for positioning said pivotally mounted member in projecting position so that the retractable means can be withdrawn from fluid flow-preventing position when the pivotally mounted member is biased towards the position in which it does not extend radially beyond said cylindrical member.

2. An apparatus comprising an elongated, generally cylindrical member having a longitudinal bore, a first aperture through the wall of said cylindrical member communicating with said bore, a second aperture through the wall of said cylindrical member communicating with said bore and vertically spaced below said first aperture, a removable member in said bore between said first and second apertures and having a through longitudinal orifice, retractable means in said bore extendable to plug said orifice for preventing fluid flow through the bore between said first and second apertures and sliding in said cylindrical member above said first aperture, a frangible pin preventing relative movement between said retractable means and said cylindrical member and holding said retractable means in flow-preventing position, a cam pivotally mounted in said cylindrical member above said first aperture and below the portion of the retractable means sliding in said cylindrical member, a spring associated with said cam biasing the cam so that it does not extend radially beyond said cylindrical member, means associated with said retractable means for holding said cam so that it projects outwardly from said cylindrical member when said frangible pin is unbroken, said retractable means extending through said cam perpendicular to its pivotal axis, said retractable means being provided with an upwardly extending projection adapted to be engaged by a well tool so that an upward force on the projection breaks the frangible pin to permit said spring to bias said cam to a non-projecting position and the withdrawal of the retractable means from said orifice.

3. An apparatus comprising a pipe section having a through bore and having a laterally enlarged portion intermediate the ends of said section, a generally cylindrical, elongated valve seat in said laterally enlarged portion, said valve seat being in communication with the bore of said pipe section and having an opening communicating externally of said pipe section, a longitudinally bored control means removably disposed in said valve seat, said control means being adapted to be removed and inserted in said valve seat by a well tool insertable into said pipe section, said control means, valve seat and laterally enlarged portion of said pipe section being proportioned to enable the control means to pass through said pipe section bore, a first aperture in said control means communicating with the bore of said control means and the bore of said pipe section, a second aperture in said control means vertically displaced from said first aperture and communicating with the bore of said control means and the opening in the valve seat com-

municating externally of said pipe section, flow preventing means disposed between the valve seat and control means intermediate the first and second apertures in the control means, means to sealingly separate the internal portion of the valve seat communicating with the second aperture from communication with the bore of said pipe section except through said control means bore, said control means having retractable means in its bore extendable to plug a reduced area within said bore between said first and second apertures for preventing fluid flow through the bore between said first and second apertures, means for releasably holding said retractable means in flow preventing position and means for releasing said holding means so that the retractable means can be withdrawn to a position permitting fluid flow from said first to said second apertures and through said control means bore.

4. An apparatus comprising a pipe section having a through bore and having a laterally enlarged portion intermediate the ends of said section, a generally cylindrical, elongated valve seat in said laterally enlarged portion, said valve seat being in communication with the bore of said pipe section and having an opening communicating externally of said pipe section, a longitudinally bored control means removably disposed in said valve seat, said control means being adapted to be removed and inserted in said valve seat by a well tool insertable into said pipe section, said control means, valve seat and laterally enlarged portion of said pipe section being proportioned to enable the control means to pass through said pipe section bore, a first aperture in said control means communicating with the bore of said control means and the bore of said pipe section, a second aperture in said control means vertically placed below said first aperture and communicating with the bore of said control means and the opening in the valve seat communicating externally of said pipe section, flow preventing means disposed between the valve seat and control means intermediate the first and second apertures in the control means, means to sealingly separate the internal portion of the valve seat communicating with the second aperture from communication with the bore of said pipe section except through said control means bore, said control means having a removable restricted orifice member in its bore between said first and second apertures, retractable means in said control means bore extendable to plug said orifice for preventing fluid flow through the bore between said first and second apertures, means for releasably holding said retractable means in flow preventing position and means for releasing said holding means so that the retractable means can be withdrawn from the orifice plugging position, and latch means for retaining said control means in said valve seat when said retractable means is in flow-preventing position.

5. An apparatus comprising a pipe section having a through bore and having a laterally enlarged portion intermediate the ends of said section, a generally cylindrical, elongated valve seat in said laterally enlarged portion, said valve seat being in communication with the bore of said pipe section and having an opening communicating externally of said pipe section, a longitudinally bored control means removably disposed in said valve seat, said control means being adapted to be removed and inserted in said valve seat by a well tool insertable into said pipe section, said control means, valve seat and laterally enlarged portion of said pipe section being proportioned to enable the control means to pass through said pipe section bore, a first aperture in said control means communicating with the bore of said control means and the bore of said pipe section, a second aperture in said control means vertically placed below said first aperture and communicating with the bore of said control means and the opening in the valve seat communicating externally of said pipe section, flow preventing means disposed between the valve seat and control

means intermediate the first and second apertures in the control means, means to sealingly separate the internal portion of the valve seat communicating with the second aperture from communication with the bore of said pipe section except through said control means bore, said control means having a removable restricted orifice member in its bore between said first and second apertures, retractable means in said control means bore extendable to plug said orifice for preventing fluid flow through the bore between said first and second apertures, means for releasably holding said retractable means in flow-preventing position, a member pivotally mounted in said control means, means biasing said pivotally mounted member towards a position in which it does not extend radially beyond said control means, means associated with said retractable means for positioning said pivotally mounted means so that it projects outwardly from said control means to latch it in said valve seat when said retractable means is held in flow-preventing position, and means for releasing said holding means and said means for positioning said pivotally mounted member in projecting position so that the retractable means can be withdrawn from fluid flow-preventing position when the pivotally mounted member is biased towards the position in which it does not extend radially beyond said control means.

6. An apparatus comprising a pipe section having a through bore and having a laterally enlarged portion intermediate the ends of said section, a generally cylindrical, elongated valve seat in said laterally enlarged portion, said valve seat being in communication with the bore of said pipe section and having an opening communicating externally of said pipe section, a longitudinally bored control means removably disposed in said valve seat, said control means being adapted to be removed and inserted in said valve seat by a well tool insertable into said pipe section, said control means, valve seat and laterally enlarged portion of said pipe section being proportioned to enable the control means to pass through said pipe section bore, a first aperture in said control means communicating with the bore of said control means and the bore of said pipe section, a second aperture in said control means vertically placed below said first aperture and communicating with the bore of said

control means and the opening in the valve seat communicating externally of said pipe section, flow preventing means disposed between the valve seat and control means intermediate the first and second apertures in the 5 control means, means to sealingly separate the internal portion of the valve seat communicating with the second aperture from communication with the bore of said pipe section except through said control means bore, said control means having a removable restricted orifice member in its bore between said first and second apertures, retractable means in said control means bore extendable to plug said orifice for preventing fluid flow through the bore between said first and second apertures and sliding in said control means above said first aperture, a frangible pin preventing relative movement between said retractable means and said control means and holding said retractable means in flow-preventing position, a cam pivotally mounted in said control means above said first aperture and below the portion of the retractable means 10 15 20 25 30 35 40 45 50 55 60 65 70 75 80 85 90 95 100 105 110 115 120 125 130 135 140 145 150 155 160 165 170 175 180 185 190 195
